CLAIM

The ornamental design for a heatsink-outfitted speed controller housing, as shown.

DESCRIPTION

FIG. 1 of the drawings is a front, top, and left side three-dimensional view of a heatsink-outfitted speed controller housing constructed according to the invention;

FIG. 2 is a top view of the housing;

FIG. 3 is a front view;

FIG. 4 is a left side view;

FIG. 5 is a right side view;

FIG. 6 is a rear view; and,

FIG. 7 is a bottom view.
